(57) **CLAIM**

We claim the ornamental design for 3D glasses, as shown and described.

DESCRIPTION

FIG. 1 is a perspective view of the front and top of the 3D glasses showing design of our invention;

FIG. 2 is a front elevation view of the 3D glasses;

FIG. 3 is a left side elevation view showing exterior of temple of FIG. 1;

FIG. 4 is a top perspective view of FIG. 1;

FIG. 5 is a front elevation view of FIG. 1;

FIG. 6 is a left side elevation showing exterior of the left temple view of FIG. 1;

FIG. 7 is a top plan elevation view of the 3D glasses of FIG. 1;

FIG. 8 is a left side elevation view the interior of the left temple of FIG. 1;

FIG. 9 is the rear elevation view of FIG. 1;

FIG. 10 is the bottom plan view the interior of the right temple of FIG. 1;

FIG. 11 is the bottom perspective view of FIG. 1; and,

FIG. 12 is the right side elevation view of the interior of the right temple of FIG. 1.
